NECKTIE DISPLAY CARD

Filed Jan. 16, 1926

Patented Aug. 3, 1926.

UNITED STATES PATENT OFFICE.

EMIL GLICK, OF CLEVELAND, OHIO.

NECKTIE-DISPLAY CARD.

Application filed January 16, 1926. Serial No. 81,811.

This invention has to do with the art of display cards or holders and embodies a special form of card for the displaying of wearing apparel in an attractive manner.

5 A display card embodying my invention, as shown and described herein, is adapted especially for facilitating the sale of neckwear, through it may be embodied in other adaptations, dependent somewhat on the

10 nature of the goods intended to be sold.

In the carrying out of my invention I utilize a card bearing an illustration provided with a cutout portion at the portion of the illustration intended to depict how 15 the article of wearing apparel will look in actual use. The card is formed so that such article of wearing apparel may be applied thereto so that at least a portion of the article will be visible through the cutout portion, and thus the display will indicate 20 quite graphically the appearance of the particular article when actually used.

A full understanding of the invention will be had on reference to the following 25 description in conjunction with the accompanying drawings in which Fig. 1 is a plan view of a necktie display card and a tie applied thereto and showing a preferred embodiment of the invention.

30 Figure 2 is a longitudinal sectional view of the parts that are illustrated in Fig. 1, the section being on the line 2-2 of said figure.

Figure 3 is a plan view of the display 35 card alone.

Figures 4, 5 and 6 are cross-sectional views taken on the lines 4-4, 5-5, and 6-6, respectively of Fig. 2.

As my display card is a very simple construction and its special novelty and advantages reside in its manner of use when the article of wearing apparel is applied thereto, I shall describe principally herein the way in which the article is secured to the 40 card. At the outset, however, it is to be noted that the card or holder designated 1, bears an illustration of the bust of a boy, designated 2, and is provided with a top slit 3 transversely thereof, a bottom slit 4, 45 transversely thereof, an elongated opening 5 below said bottom slit 4 with its longer dimension crosswise of the card or holder 1, and a longitudinal centrally disposed display opening 6 intermediate the slits 3 and 50 4. An upper end of the card 1 may be formed with a curved edge cutout 7 to fa-

cilitate the looping around this upper end of the necktie or article to be displayed.

Assuming that the card is to be used as a necktie display holder, designed to be 60 placed in a box or supported on a stand, or otherwise displayed, a necktie is preferably looped upon itself about centrally between its ends, as shown at 8, Fig. 2. The tie thus folded upon itself is arranged with the free 65 ends thereof in front of the card as shown at 9 in Fig. 1. The body of the folded portion of the tie is then inserted through the elongated opening 5 and passed in rear of the card 1 and that portion thereof bearing 70 the illustration 2. Then the said folded portion of the tie is passed through the upper slit 3 around the curved cut in upper end 7 of the card 1 and downwards in rear of the card and the portion of the tie previously disposed in contact with the rear side of said card.

A disposition of the necktie looped through openings, slits and around the end 80 of the card 1 in the manner described enables the pattern of the tie to be readily visible at the upper and lower portions of the card. Additionally, however, the appearance of the tie as when in use will be 85 shown because of the provision of the longitudinal display opening 6 which is shaped like a tie and is so located in relation to the illustration 2 of the bust of the boy pictured on the card, that the appearance of the tie under actual conditions of use will 90 be graphically depicted.

The portion of the card 1 between the slit 4 and the opening 5 may be provided with the word "greetings", or with an inscription appertaining to a birthday, to 95 Christmas, or the like. If the tie is looped through the opening 5, as shown in Fig. 1, the inscription will be visible, being designated 10. However, should the article of the invention be used at a time of the year 100 when the inscription might not be appropriate, it may be looped through the slit 4 over the inscription 10, and permitted to hang down over the card in such a manner as to cover the inscription. If desired, the card 105 1 may be provided with flanges 11 to support it somewhat spaced from the bottom of a box in which it may be located, or the card may have a pedestal extension of some sort to support it in a display position upon 110 a counter or similar supporting means.

In conclusion it is noted that the display

opening 6 is located in relation to the loop 2 in a position corresponding with the position in which the article displayed will be worn when in use.

5 Having thus described my invention what I claim as new and desire to secure by Letters Patent is:

1. As a new article of manufacture, a display card having a slit 3 near its upper end and an opening 5 at its lower end, with an illustration on its face between the slit and opening, also having a cut-out portion 6 forming a part of the illustration and shaped like a neck-tie when tied and in use, the 10 said parts permitting a neck-tie to be looped about the card at the portion above the slit, passed back in rear of the card so that the pattern of the tie may be visible through the cut-out portion 6 and thus resemble a neck-tie as actually worn, the opening 5 being adapted to have the neck-tie passed therethrough from the back to the front of the card so as to hang down and show its 20 pattern to a large extent as compared with the showing through the cut out portion 6.

2. As a new article of manufacture, a display card for necktie comprising a body bearing on its surface the illustration of the 25

bust of a person, the card being cut away at a point merging into the illustration to 30 provide an opening having the outline of a necktie, and said card being equipped with means for enabling application thereto of a necktie, the major portion of which will be covered by the card so that said necktie may 35 be visible through the cutout opening associated with the illustration, whereby the manner in which the necktie will appear when worn is graphically displayed when the said necktie is applied to the card. 40

3. As a new article of manufacture, necktie display card consisting of a body provided with a slit at its upper portion and an opening at its lower portion, the said card body bearing on its surface between said slit 45 and opening an illustration of the bust of a person accompanied by a display opening forming a continuation of said illustration and having outline of a necktie, the said slit and opening being so arranged that a 50 necktie may be looped therethrough to pass in rear of the body of the card and to be visible through the said display opening.

In testimony whereof I affix my signature.

EMIL GLICK.
